JAMES T. JEFFRIES AND EUGENE E. HENRY, OF ASTORIA, OREGON.

POINT-PROTECTOR FOR PENCILS AND THE LIKE.

1,199,555.

Specification of Letters Patent. Patented Sept. 26, 1916.

Application filed January 10, 1916. Serial No. 71,333.

To all whom it may concern:

Be it known that we, JAMES T. JEFFRIES and EUGENE E. HENRY, citizens of the United States, and residents of Astoria, 5 Clatsop county, Oregon, have invented a new and useful Improvement in Point-Protectors for Pencils and the like, of which the following is a specification.

This invention relates generally to devices 10 used in connection with lead pencils, or other pointed articles for protecting the points thereof.

When pencils are carried in the pocket, the points are frequently broken and there- 15 by cause much inconvenience. Furthermore, the lead of pencils often discolors or otherwise soils the clothing with which it comes in contact. Pointed articles of any type are dangerous when carried in the pocket.

20 One of the main objects of our invention is to provide a point protector which may be conveniently used with a pencil or other pointed article, so as to protect the point, and eliminate the objectionable features pre- 25 viously mentioned.

In the accompanying drawings: Figure 1 is a side elevation showing the pointed end 30 of a pencil with our point protector used in connection therewith. This view is en- 35 larged, and the full lines show the device in position for allowing the pencil to be used, while the broken lines indicate the position of the device after it has been moved forward so as to protect the point; Fig. 2 is a left-end elevation of Fig. 1; Fig. 3 is a view similar to Fig. 1, but showing another type 40 of construction; Fig. 4 is a left-end elevation of Fig. 3; Fig. 5 is a vertical section taken on line 5—5 of Fig. 3; and Fig. 6 is an elevation showing still another alter- 45 nate type of construction.

In these drawings, a pencil, *a*, of any standard make is provided with a pointed cone-shaped end *b* and lead point *c*.

45 Referring first to Fig. 1, *d* is an open-end- 50 ed cylindrical body, the outer end of which is contracted so as to form a cone-shaped portion *e*, adapted to fit over and form a seat for the cone-end *b* of the pencil; at the 55 same time permitting the point *c* of the pencil to project beyond to permit its use for writing. *f* is an annular rib extending circumferentially around the cylindrical body *d* in the position shown. The inner end of the body *d* is provided with a rolled double thread *g* and an annular rib *h*. Said inner

end is further provided with longitudinal slots *i* located diametrically opposite each other, and which allow for the expansion of this end of the body. A ring *j* encircles the 60 body *d*, having a sliding fit thereon, and is confined between the ribs *f*, *h*.

In actual use, the general operation of this device is as follows: The ring *j* is first moved to a position adjacent the rib *f*, so 65 that when the device is placed on the pencil, *a*, the inner end of the body *d* will expand, due to the root diameter of the inwardly rolled threads riding on the body of the pencil. When the device has been moved 70 to the extreme position as shown in full lines in Fig. 1, the ring *j* is moved toward the inner end of the body *d*, whereupon it will bear down on the expanded end of the latter and force the inwardly rolled thread 75 *g* into the body of the pencil, thereby clamping the device firmly in place. When the protector is in this position it allows free use of the pencil.

When the pencil is not in active use, the 80 point *c* may be protected by merely twisting the device to the left, which movement causes the threads to project the device to the position shown in the broken lines in Fig. 1. In this position the point *c* will be 85 entirely within the coned end *e* of the device and will be safely protected until such time as it is again to be used.

In Fig. 3, *k* is an open-ended cylindrical body similar to the body *d*, except that the 90 contracted end *e* is omitted, and the rib *f* is replaced by a lug *m*. The inner end of the body is provided with a thread *n*, rib *o*, slots *p* and ring *l*, which are identical with the corresponding parts shown in Fig. 1. 95 A cylindrical body *q*, relatively telescopic- 100 over the body *k*, is provided with an annular rib *r*, a slot *s*, adapted to receive the lug *m*, and a contracted expandible forward end *t*, which consists of normally converg- 105 ing resilient fingers *u*.

In operation, the device is placed on the pencil and clamped in position in the same manner as shown in Fig. 1. The advantage of this construction, over that shown in Fig. 1, lies in the fact that when the pencil is to be resharpened it is not necessary to remove the device from the pencil. In this case the body *q* is merely telescoped back on the body *k*, whereupon the resilient fingers *u* 110 will ride over the body of the pencil and allow the entire end of the latter to be pro-

jected. In this view, the parts are shown in position for protecting the point *c*, and when the pencil is to be used, the body *k* is merely twisted to the right, which causes the 5 pencil and the device to be relatively moved so as to project the point *c* only.

In Fig. 6 we have shown another modified and simpler construction, which consists of a cylindrical body *v*, provided with a contracted cone-end *w*, the end of which is open so as to allow the point of the pencil to be projected therethrough. The inner end of the body *v* is provided with an annular rib *x*, and a rolled thread *y*. In this construction, the slots are omitted, thereby making the inner end non-expansible, and when using this type of device it is threaded entirely upon the pencil, instead of allowing the same to be first placed in position and 20 then clamped, as shown in the other views.

We claim:

1. A point protector comprising an open-ended cylindrical body provided with a tapered outer end, an expansible threaded inner end, the threads of which are rolled inwardly, and means for contracting the 25 expansible end.

2. A point protector comprising an open-ended cylindrical body provided with a tapered outer end, an expansible threaded inner end, the threads of which are rolled inwardly, and a ring longitudinally movable 30 on the body.

3. A point protector comprising an open-ended cylindrical body, a sleeve telescopic 35 on said body and provided with a tapered outer end, said tapered end being formed of resilient, converging members, means for limiting the movement of the sleeve on the body, an expansible threaded inner end on 40 said cylindrical body, the threads of which are rolled inwardly, and means for contracting the expansible end.

4. A point protector comprising an open-ended cylindrical body, a sleeve telescopic 45 on said body and provided with a tapered outer end, said tapered end being formed of resilient, converging members, means for limiting the movement of the sleeve on the body, an expansible, threaded inner end on 50 said cylindrical body, the threads of which are rolled inwardly, a ring longitudinally movable on the body, and means for limiting the movement of such ring.

5. A point protector comprising an open-ended cylindrical body provided with a threaded inner end the threads of which are rolled inwardly, a sleeve telescopic on the outer end of said body and provided with a tapered outer end, said tapered end being 60 formed of resilient, converging members and means for limiting the movement of the sleeve on the body.

JAMES T. JEFFRIES.
EUGENE E. HENRY.
